MOVABLE REED MECHANISM

Carl D. Brown, Hopedale, Mass., assignor to
 Draper Corporation, Hopedale, Mass., a corporation of Maine

Application November 6, 1934, Serial No. 751,737

10 Claims. (Cl. 139—188)

The present invention pertains to fly shuttle looms, and more particularly to the reed holding and controlling instrumentalities of such looms.

There exists in the prior art a reed mechanism, 5 commonly called loose reed mechanism, wherein the reed is positively locked to the lay during the time the shuttle is normally in flight but is released at a predetermined point in each forward beat of the lay to allow the reed to yield rearwardly if the shuttle becomes trapped in the shed. Such reed mechanisms are usually found on automatic shuttle changing looms. The reed is movable by a very light pressure from a trapped shuttle at the so-called protection point, 10 and the reed must be more firmly held during the beating in of the filling. The holding of the reed when the lay is at front center is usually accomplished by a positive locking means.

A further well known type of reed mechanism 20 is the yielding reed mechanism (sometimes erroneously called loose reed mechanism). Such reed mechanism is constructed to provide for a limited rearward yielding of the reed when the lay is at front center. The yielding of the reed compensates for variations in the diameter of successive picks of filling thread, tends to prevent thick and thin places, and otherwise improves the appearance of the cloth. Such mechanisms are usually found on non-automatic looms 25 and bobbin changing looms particularly adapted for weaving silk, artificial silk or very fine cotton.

The loose reed and yielding reed mechanisms of the prior art have not been combined in one loom and, so far as I am aware, prior to the present invention there has been no single reed mechanism specifically adapted to both loose reed and yielding reed functions.

It is, accordingly, an object of the present invention to provide a reed controlling mechanism 40 for movable reeds which mechanism shall provide for a slight yielding of the reed at the time of beat-up and shall also provide for positively limiting such rearward movement during the time the shuttle is normally in flight and for releasing the reed at a predetermined point to permit the reed to move rearwardly a comparatively greater distance if, at such time, the shuttle is trapped in the shed.

Other objects will be hereinafter more specifically enumerated, or will become apparent as the description proceeds.

The preferred embodiment of the invention, which is herein disclosed, includes a reed which 55 is pivotally mounted to pivot about its upper rib,

the movement of the reed being controlled through a filter which bears directly against the lower reed rib. A shaft extends lengthwise of the lay therebeneath and is positively held from oscillating during the time the lay is at front center and during the time the shuttle is normally in flight. The filter is supported from the shaft by connections which permit the filter, and reed, to yield slightly even when the shaft is locked. This slight yielding is opposed by strong spring means and is preferably limited to the amount reasonably necessary to provide the "yielding" reed function above mentioned. The positive stop means for the oscillatable shaft free the shaft at a predetermined point 10 in each forward beat of the lay, thereby allowing the shaft, connections, filter and reed to move the comparatively great distance necessary to accommodate a trapped shuttle.

The said preferred embodiment is illustrated 20 in detail on the accompanying drawings, of which:

Fig. 1 is a perspective view, partly in section, from the back of the lay;

Fig. 2 is a sectional elevation showing a trapped 25 shuttle; and

Fig. 3 is a view similar to Fig. 2 but showing the parts in normal operative position.

The loom which I have selected as best illustrating an adaptation of the present invention 30 includes many parts or mechanisms which are old and well-known in the art. Accordingly, many such parts and mechanisms are not illustrated on the drawings, while others are shown as examples of constructions which may be 35 utilized.

The loom, as shown, includes right and left hand loom sides 1 and 2, respectively, which are connected by cross-members including breast beam 3 at the front of the loom. The loom is 40 controlled through a shipper handle 4 which is movable for operating controlling rods such as 5 and 6. The shipper handle is pulled toward the front of the loom, as in Fig. 3, when in running position and is moved rearwardly, as in 45 Fig. 2, to stop the loom. A rod 7, slidably mounted on the loom frame, may be moved forwardly by devices hereinafter described, such forward movement serving to stop the loom in the manner more fully disclosed in patent to Lindsjo, 50 et al., No. 1,850,306, granted March 22, 1932.

A lay 8 is mounted on lay swords 9, 9 for reciprocation toward and from the front of the loom in the usual manner. A reed 10 is mounted 55 on the lay so as to normally move therewith but

to be capable of rearward movement thereon at certain times. The particular reed shown is thus movable by virtue of the fact that its upper rib 11 is loosely mounted in a groove in the hand rail 12 whereby the reed can pivot rearwardly about the rib 11. The reed is held forwardly against the lay by a suitable member such as filter 13 which is controlled as hereinafter described.

10 A shuttle 14 is picked along the lay and lays filling in the shed formed of warp W, the filling being laid in front of the reed and beaten in by the latter, all in the usual manner. The reed is capable of a rearward yielding movement at 15 the time of beat-up (that is, when the lay is at front center and the filling being beaten into the cloth) such yielding serving to compensate for irregularities in thickness or spacing of the filling.

20 A rock shaft 15 extends widthwise of the loom beneath the lay. This shaft is mounted so as to be capable of oscillation at times but at other times is positively locked. The rock shaft is so locked at the time of beat-up by means of 25 arms 16, 16 fixed thereto which arms engage beneath fixed stops 17, 17 on the loom sides. Yieldable means support the filter 13 from the rock shaft. As shown, arms 18, 18 are fixed to the rock shaft and extend upwardly and rearwardly 30 to receive a fixed shaft 19. Brackets 20, 20, which are fixed to the filter, have bearing portions by which they are oscillatably mounted on the shaft 19. Coiled springs 21, 21 each have one end fixed with respect to the shaft and the other 35 end fixed to a bracket 20. The springs thus yieldingly oppose rearward movement of the reed at the time of beat-up. The rearward movement of which the reed is capable at this time is limited by cooperating stop shoulders on the arms 40 18 and brackets 20, as is clearly shown in Fig. 1.

45 The manner in which the parts just described operate to fulfill the function of a yielding reed will be apparent. It may be noted, however, that the arms 18, 18 are adjustably secured to the shaft 15 and that adjustment of the arms about the shaft serves to adjust the distance between the limiting stop shoulders on the arms and brackets. The arms can be adjusted so as to entirely close the distance between the stop shoulders, this preventing the yielding of the 50 reed at the time of beat-up.

55 As the lay moves rearwardly, an arm 22, which may be integral with the right hand arm 16, engages in a notch in stop lever 23. This lever is pivoted to the loom frame at 24, guided by a rod 25, and pulled forward toward a limiting shoulder 26 by a spring 27. The lever is set to be engaged by the arm 22 when the lay is about half way back on its rearward movement, which is about 60 the time the shuttle is picked. The arm moves away from the lever at a predetermined point in the forward movement of the lay, such point being the point in the loom cycle where the shuttle is supposed to have completed its flight. 65 Thus, the shaft 15 is positively locked during the time the shuttle is normally in flight, such locking of the shaft serving to lock the reed against moving rearwardly more than the limited amount above mentioned.

70 When the shaft 15 is released from control of lever 23, as just described, the reed is capable of moving rearwardly a comparatively greater amount to prevent damage to the warp if the shuttle becomes trapped in the shed as in Fig. 2. 75 However, the shaft, filter and reed should not

at this time be entirely uncontrolled. There is accordingly provided an arm, link 28 and spring 29 comprising a toggle for yieldingly opposing rearward movement of the reed. The spring 29 may be very light compared to the springs 21. 5 This toggle device is more fully disclosed in prior patent to Lindsjo, No. 1,956,075, granted April 24, 1934.

In the specific embodiment above described, the yieldable means supporting the filter member 10 for limited rearward yielding at the time of beat-up is, in turn, bodily supported by the second yieldable means which permits the comparatively greater yielding of the filter when the shuttle becomes trapped. In the specific embodiment 15 above described, the locking means for the second yieldable means is inoperative to lock the reed against its limited rearward yielding at the time of beat-up and is also inoperative to prevent such limited yielding when the shuttle is in flight. 20 I find that in some looms, such as shuttle change looms for instance, the susceptibility of the reed to a slight rearward movement while the shuttle is in flight is not objectionable if such movement is positively limited to a comparatively small 25 amount.

It will be noted that since the invention as hereinabove claimed consists of a mechanism adapted to both the yielding reed and loose reed functions, the invention is not limited to the specific mechanism which is herein disclosed.

Having fully disclosed the preferred embodiment of the invention, I claim:

1. In a fly shuttle loom, a reciprocating lay, a shuttle, a reed mounted on the lay for rearward movement relative thereto at the time of beat-up, means yieldingly opposing said rearward movement of said reed at the time of beat-up to thereby compensate for irregularities in the filling, and means positively limiting said rearward movement during the time the shuttle is normally in flight, said last named means releasing said reed at a predetermined point in each forward beat of the lay to thereby permit the reed to be moved rearwardly by a trapped shuttle. 40

2. In a fly shuttle loom, a reciprocating lay, a shuttle, a reed mounted on the lay to yield rearwardly a limited amount at the time of beat-up and to yield a comparatively greater amount when the shuttle becomes trapped, and means 50 operative to prevent the reed from yielding said comparatively greater amount during the time the shuttle is normally in flight, said means being released at a predetermined point in each forward beat of the lay to thereby allow the reed to yield 55 said comparatively greater amount when the shuttle becomes trapped.

3. In a fly shuttle loom, a reciprocating lay, a shuttle, a reed mounted on the lay to yield rearwardly a limited amount at the time of beat-up 60 and to yield a comparatively greater amount when the shuttle becomes trapped, and positive locking means for locking said reed against yielding said comparatively greater amount during the time the shuttle is normally in flight, said means being 65 inoperative to lock said reed against yielding rearwardly said limited amount at the time of beat-up, and said means releasing said reed at a predetermined point in each forward beat of the lay.

4. In a fly shuttle loom, a reciprocating lay, a 70 shuttle, a reed mounted on the lay for rearward movement relative thereto, a member opposing rearward movement of said reed, yieldable means supporting said member for rearward yielding of the member and reed at the time of beat-up, 75

means supporting said first named means for comparatively greater rearward yielding of said member and reed when said shuttle becomes trapped, and locking means cooperating with said second named means to lock said member and 5 reed against said comparatively greater rearward yielding during the time the shuttle is normally in flight.

5. In a fly shuttle loom, a reciprocating lay, a shuttle, a reed mounted on the lay for rearward 10 movement relative thereto, a filter for controlling said reed, yieldable means supporting said filter for limited rearward yielding of the filter and reed at the time of beat-up, a second yieldable means supporting said first named means to permit comparatively greater rearward yielding of said filter 15 and reed when said shuttle becomes trapped, positive locking means for locking said second means against yielding during the time the shuttle is normally in flight and at the time of beat-up, said 20 locking means being released at a predetermined point in each forward beat of the lay.

6. In a fly shuttle loom, a reciprocating lay, a shuttle, a reed mounted on the lay for rearward movement relative thereto, a filter for controlling said reed, yieldable means supporting said filter for limited rearward yielding of the filter and reed at the time of beat-up, an oscillatable member on the lay supporting said yieldable 25 means and filter, spring means opposing oscillation of said member, and positive locking means for locking said member against oscillation at the time of beat-up and during the time the shuttle is normally in flight, said locking means being released at a predetermined point 30 in said forward beat of the lay.

7. In a fly shuttle loom, a reciprocating lay, a shuttle, a reed mounted on the lay for rearward movement relative thereto, a rock shaft mounted on the lay, a filter for controlling said 40 reed, means carried by said rock shaft for supporting said filter for limited rearward yielding relative to the rock shaft, said rock shaft being oscillatable to permit a comparatively greater rearward yielding of said filter when the shuttle

becomes trapped, and means positively locking said rock shaft against oscillation during the time the shuttle is normally in flight.

8. In a fly shuttle loom, a reciprocating lay, 5 a shuttle, a reed mounted on the lay for rearward movement relative thereto, an oscillatable rock shaft on the lay, a filter for controlling said reed, a plurality of arms secured to said rock shaft, means on said arms for yieldingly supporting said filter for limited rearward movement of the latter and the reed at the time of beat-up, means operative as the lay moves rearwardly to positively lock said rock shaft against oscillation, said means releasing said rock shaft as the lay moves forwardly, and additional means 10 for positively locking said rock shaft against oscillation at the time of beat-up.

9. In a fly shuttle loom, a reciprocating lay, 15 shuttle, a reed mounted on the lay for rearward movement relative thereto, means yieldingly opposing said rearward movement, positive stop means for limiting said rearward movement of the reed at the time of beat-up and during the time the shuttle is normally in flight, said stop means releasing said reed at a predetermined 20 point in each forward beat of the lay for further rearward movement of the reed by a trapped shuttle, and an adjustable stop capable of being adjusted to entirely prevent rearward movement of said reed at the time of beat-up.

10. In a fly shuttle loom, a reciprocating lay, 25 a shuttle, a reed mounted on the lay for rearward movement relative thereto, a filter for controlling said reed, an oscillatable rock shaft on the lay, means carried by said rock shaft for yieldingly supporting said filter, means for locking said rock shaft against oscillation at the time of beat-up and during the time the shuttle is normally in flight, said locking means releasing said rock shaft at a predetermined point in each 30 forward beat of the lay, and adjustable stop means capable of being adjusted to entirely prevent rearward movement of said reed at the time of beat-up.

CARL D. BROWN. 45
